UNITED STATES PATENT OFFICE.

TEODOR SOSNOWSKI, OF CHICAGO, ILLINOIS.

BURIAL-CASKET.

No. 922,819.

Specification of Letters Patent. Patented May 25, 1909.

Application filed May 22, 1908. Serial No. 434,887.

To all whom it may concern:

Be it known that I, TEODOR SOSNOWSKI, a citizen of the United States, residing at Chicago, in the county of Cook and State of Illinois, have invented certain new and useful 5 Improvements in Burial-Caskets, of which the following is a specification.

The object of this invention is to construct a metallic casket which shall have the general appearance and finish which perfectly imitates a wooden casket and which will be stronger and more permanent in its character than a casket constructed of wood. The casket is, furthermore, intended to be 15 lighter than a wooden casket of similar dimensions; and the invention is one which permits great variation in the design or style of the casket and enables the casket to be constructed without any visible screw or bolt 20 fastenings, so that the smooth metal surface can be grained to perfectly imitate mahogany or other costly wood.

Another object of the invention is to provide suitable means for securing the lining to the casket and to so construct the casket as a whole that it will have a smooth, rectangular, inner wall, regardless of the configuration of the outer or exposed wall of the casket.

The invention consists in the features of 30 construction and combination of parts hereinafter described and claimed:

In the drawings, Figure 1 is a perspective view of the casket, showing one of the corners partially broken away; Fig. 2 a longitudinal sectional view of the same; and Fig. 3 a cross sectional view of the casket, showing a slightly different exterior design.

The casket, as shown in Figs. 1 and 2, is of generally rectangular shape and comprises 40 side walls 4 and end walls 5 of the usual dimensions. Since the construction of the side and end walls is the same, except as regards length, a description of one of the walls will be understood as applying to the remaining walls. Each of the walls comprises an inner flat metallic section 6 and an outer rounded metallic section 7, which latter is intended to be curved or bent to give style and beauty to the casket, it being understood that the configuration of the outer wall may be changed 45 or modified to meet the design intended. As shown in Fig. 2, the outer wall comprises a base portion 8, the lower edge 9 of which is inwardly turned and provided with a flange 10 which lies parallel with the lower edge of 50 the inner flat wall 6 and is preferably united thereto by solder. The base 8 merges into a lower neck 11 which is inwardly bent toward the inner wall and preferably united thereto by means of solder. The body of the outer 6 wall may be either outwardly bulged, as shown in Fig. 2, or inwardly rounded, as shewn in Fig. 3, or may be otherwise formed to meet the required design. The upper portion of the wall merges into an upper neck 6 12 which, like the lower neck, is inwardly bent or formed to lie close against the inner wall near the upper edge thereof, to which wall the upper neck is preferably secured by means of solder. The metal of the outer 70 wall, above the neck 12, is outwardly bent to provide a ledge or shelf 13, the outer edge of which terminates in a bead or roll 14. The upper edge of the inner straight wall is outwardly bent and reversed to provide a channeled flange 15 which overlies and rests upon 75 the inner edge of the ledge or shelf 13, the contacting surfaces being preferably united by solder. The bottom of the body of the casket is in the form of a metallic wall 15^a, 80 the edges of which are flanged and soldered to the side and end walls of the casket. The structure is further reinforced by a wooden floor 16 which underlies the bottom metallic plate and is secured in place by means of 85 screws or nails 17 driven through the walls of the casket and through the side flanges of the bottom plate. This construction is one which provides a strong and rigid body for the casket, in that the weight of the body 90 within the casket will be largely sustained by the ledge or shelf 13 upon which the channeled flange on the inner wall of the casket rests. This serves to distribute the weight 95 and prevents possible falling of the inner wall of the casket which might take place if the soldered connections alone were relied upon to secure the inner and outer walls. Between the walls of the casket is preferably 100 located a wooden panel 18 which receives the ends of screws 19 entered through the handle plates 20 on the outside of the side walls of the casket. The inner flat walls 6 are secured to the wooden panel by means of 105 screws or nails 21 which are driven into the wood from the inside and are hidden and covered when the casket is lined. The channeled flange 15 has entered thereinto a wooden strip 22 which serves the double function of reinforcing the channeled flange 110 and of providing a suitable attachment for the lining of the casket. The edges of the

side and end walls are preferably united by solder 23 which is filled into the corner in considerable amount so that a perfect joint is provided which is incapable of detection 5 after the casket has been finished.

The cover of the casket comprises an outer wall 24 and an inner wall 25. The outer wall can be bent or formed to present a rounded or otherwise ornamental appearance, and the 10 outer wall terminates in a side wall or flange 26, the lower edge 27 of which is beaded and adapted to fit into the space between the bead 14 and the channeled flange 15, which 15 space, in the form of a groove, extends entirely around the casket. In the form shown, the outer wall of the cover is shouldered at the angle 28 between the side wall and the top wall of the cover, and a strip 29 of wood is inserted between the shoulder so 20 formed and the bead 27, which reinforces the edge of the cover and at the same time serves to engage the edge 30 of the inner wall 25 of the cover, which is preferably soldered to the bead 27 at this point. The cover is provided 25 with a window 31 which is closed by double door panels 32. The cover can be provided with ornamental panels 33 which are formed independently of and secured to the top of the cover by soldering. The cover is secured 30 to the body of the casket by means of clamps 34 which are held in place by means of screws 35 entered through the side wall or edge 26 of the cover and into the wooden strip 29 adjacent thereto.

35 It is preferably intended to form the inner and outer walls of the casket out of zinc which is a non-corrodible metal and one which renders the soldering operation peculiarly effective and permits the corners and 40 walls of the casket to be perfectly formed and as durable as the zinc walls of the casket itself. The panels interposed between the walls serve to prevent denting of the outer or ornamental wall of the casket, and at the 45 same time provide sufficient body for the securing of the handle plates to the sides of the casket. The casket is so formed that there will be no exposed metallic edges and no visible nails or rivets, so that the metal surface 50 can be perfectly grained to imitate costly wood, which imitation is so perfect that it is practically impossible to tell the casket of the present invention therefrom.

The arrangement is one which permits wide 55 variations in the design and external appearance of the casket without departing from the general principle of the present invention. It will be noted that the design illustrated in Fig. 3 lacks the lower attaching 60 neck 11, but that it embodies the same structural features which characterize the structure in Fig. 2. The casket is one which will not be warped, rotted or otherwise affected by moisture, will be impervious to the

attack of worms, and which possesses all of 6 the ornamental features characteristic of a wooden casket, and, if desired, can be much more lightly constructed.

The invention is one which differs from an ordinary single walled metallic casket in that 70 it permits the casket to be constructed in such manner as to provide a smooth inner wall adapted to receive and hold the body, and an ornamental outer wall in simulation of a wooden casket. Furthermore, the double walled metallic casket of the present invention permits the use of much lighter metal than could be used in the case of a single walled metallic casket designed to accommodate the same weight. The construction, 80 furthermore, is one which permits the cover to be sealed onto the body of the casket by filling the groove or channel around the upper edge of the casket with solder, cement, or other sealing substance prior to the application 85 of the cover in place; and this operation can be very quickly performed, especially in the case of a zinc casket, by reason of the ease with which the solder can be applied to such metallic surfaces. 90

What I regard as new and desire to secure by Letters Patent is:

1. A casket comprising an inner metallic wall and an outer metallic wall of ornamental configuration bent or formed to abut against 95 the inner wall at suitable points, and attaching means, as solder, for uniting the two walls at the adjacent points, substantially as described.

2. A burial casket comprising an inner 100 plain wall and an outer wall having an ornamental configuration and united with an inner wall along its lower or base edge and provided, near its upper edge, with an attaching neck bent to abut against the inner wall, 105 means, as solder, for uniting the inner and outer walls at their abutting points, the outer wall terminating in an outwardly projecting ledge or shelf beaded around its edge, and the inner wall terminating, at its upper 110 edge, in an outwardly extending channeled flange resting upon the edge of the ledge or shelf, and a cover provided with an edge 115 adapted to fit into the space intermediate the beaded edge of the ledge or shelf and the channeled flange, substantially as described.

3. A burial casket comprising an inner plain wall and an outer wall having an ornamental configuration and united with an inner wall along its lower or base edge, and provided, near its upper edge, with an attaching neck bent to abut against the inner wall, 120 means, as solder, for uniting the inner and outer walls at their abutting points, the outer wall terminating in an outwardly projecting ledge or shelf beaded around its edge, and the inner wall terminating, at its upper 125 edge, in an outwardly extending channeled

flange resting upon the edge of the ledge or shelf, wooden panels entered into the space intermediate the inner and outer wall, a wooden strip entered into the channeled flange, and a double walled metallic cover provided with an edge adapted to fit between the beaded edge of the ledge or shelf and the channeled flange, substantially as described.
